UNITED STATES PATENT OFFICE

RALPH Z. HOPKINS, ALBERT E. FELLERS, AND HARLEY D. RAYMOND, OF DETROIT, MICHIGAN, ASSIGNORS TO HUDSON MOTOR CAR COMPANY, OF DETROIT, MICHIGAN, A CORPORATION OF MICHIGAN

OIL OR GAS BURNER

Original application filed May 26, 1928, Serial No. 280,764. Divided and this application filed April 1, 1930. Serial No. 440,639.

This invention relates to burners or heaters especially, although not exclusively, adapted for use in connection with drawing furnaces or the like of the type disclosed and claimed 5 in our prior application Serial No. 280,764, filed May 26, 1928, now Patent No. 1,841,533, issued January 19, 1932, of which this case is a division.

The invention has for an object to provide 10 a burner or heater having a combustion chamber structure of such character as to permit the use of either liquid or gaseous fuel.

Another object of the invention is to provide a heater or burner unit so constructed as 15 to be readily detachable from the remainder of the furnace or oven structure and of a portable character, so as to be readily replaceable by another spare unit, thereby permitting relining and other necessary repairs 20 without shutting down the whole plant, said burner unit being so organized as to permit the ready and convenient renewal of the combustion chamber lining.

A further object of the invention is to provide 25 a burner unit having provision for the circulation of air therethrough to and from the oven, whereby the heat may be fully and efficiently utilized, but in which the burner is at the same time adequately cooled.

The foregoing and other objects of the invention, together with means whereby the latter may be carried into effect, will best be understood from the following description of a preferred construction thereof illustrated 35 in the accompanying drawings. It will also be understood, however, that the particular construction and arrangement described and shown have been chosen for purposes of exemplification merely, and that said invention, 40 as defined by the claims hereunto appended, may be otherwise embodied without departure from the spirit and scope thereof.

In said drawings,

Fig. 1 is a diagrammatic plan view of the 45 complete furnace showing the relation of the heater or burner to the oven.

Fig. 2 is an end elevation looking from the inlet end of the oven, or from the left in 50 Fig. 1.

Fig. 3 is a transverse vertical section, taken

substantially on the line 3—3, Fig. 1, of a burner unit.

Fig. 4 is a longitudinal vertical section taken substantially on the line 4—4, Fig. 3.

Fig. 5 is a horizontal section taken substantially on the line 5—5, Fig. 4.

Fig. 6 is an enlarged detail longitudinal section of the parts adjacent the burner.

Fig. 7 is an outside end elevation of the parts shown in Fig. 6.

The apparatus as a whole includes an oven or tunnel unit, generally indicated at A in Figs. 1 and 2, a separate heater or burner unit, generally indicated at B, and detachable conduit connections, generally indicated at 65 C, whereby the hot products of combustion in the burner unit B, together with a certain amount of air heated thereby, may be circulated in a substantially closed circuit through said units.

The provision of a separate detachable burner unit B for the drawing oven makes it possible to employ a spare burner unit, so that it is unnecessary, in case relining or other 75 repairs are required in the heater, to shut down the entire plant. On the contrary, by disconnecting the conduit connections C, as hereinafter more fully described, the disabled heater may be removed and replaced by a spare heater, whereupon the necessary

repairs can be made at leisure while the furnace continues in operation. In order to facilitate this, the burner or heater unit is supported in elevated position by an open frame work comprising transverse structural members 20 and legs 21 providing a space beneath the burner unit proper to receive the platform of an industrial truck which, when 80 repairs are needed, may be run under the unit to lift and carry the same away and in a 85 similar manner to replace it by the spare unit.

As shown in Fig. 3, longitudinal angle iron bars 200 are mounted at each side of the frame along the underside of the members 20, these bars having vertical flanges acting as guides for the truck platform L when inserted beneath the members 20. The bars 200 also have inwardly extending horizontal flanges adapted to overlie the truck platform L and receive the upper thrust thereof when 90 95 100

the lift platform is elevated to lift and carry the burner unit.

Referring particularly to Figs. 3 to 7, the burner unit proper, to which the present invention particularly relates, comprises a preferably sheet metal casing 22 to which the frame members 20 are riveted or otherwise permanently secured, said casing having a fire brick lining 23 and enclosing a circulation chamber 24. At one end the casing 22 is provided with an opening to receive a thimble 25 removably seated therein, said thimble comprising spaced co-axial inner and outer members or walls 27 and 28 connected by bolts 26. Within the circulation chamber 24 is a combustion tube or tubular combustion chamber 29 carried by fire brick supports 30 within said circulation chamber and spaced from the walls of the latter by crossed angle bars 31. The combustion tube 29 communicates at one end, as shown at 32, with the circulation chamber 24 and at its opposite end is enclosed by the inner member 27 of the thimble 25. Said combustion tube is of relatively small diameter in proportion to its length and has relatively thin section walls composed of separate blocks or tiles of highly refractory material, such as a suitable carbonitrid composition.

Supported by the thimble 25 in alignment with the combustion chamber 29, so as to direct its flame into the latter through a suitable Venturi bushing 33 of refractory material, is a burner proper, generally indicated at D, said burner being of any approved and suitable type capable of employing either oil or gas as a fuel. It will, of course, be understood that the air necessary to support combustion is supplied to or about the burner and enters the mouth of the bushing 33 with the fuel.

The space 34 between the inner and outer members of the thimble 25 communicates with the circulation chamber 24 around the combustion tube 29 immediately adjacent the burner end of said tube and also communicates, outside the casing, with the outer air through suitable air inlets 35 controlled by a manually rotatable ring damper 36, whereby the amount of air admitted to the circulation chamber can be controlled.

The construction and arrangement of parts above described adapts the apparatus for use with either liquid or gaseous fuel. The long thin walls of the combustion tube absorb the interior heat quickly and transfer it quickly to the air in the circulation chamber by which said combustion tube is completely surrounded. The fresh air admitted through the space 34 around the burner cools the hottest end of the combustion tube. As a result, overheating of the combustion tube is effectually prevented and the heat thereof transferred to the air which, as hereinafter explained, is circulated through the oven. For efficient

heating by gaseous fuel a long thin combustion chamber is required, whereas oil burning furnaces, as heretofore constructed, have required a larger combustion chamber to prevent overheating. The present construction permits the use of liquid fuel in a combustion chamber of the type required for the most efficient use of gaseous fuel. Renewal of the combustion chamber tiles can, when necessary, be readily effected by removing the thimble 25 and working through the opening in the end of the casing 22.

The conduit connections C above referred to include a supply conduit 42 leading from the circulation chamber 24 adjacent the burner end of the combustion chamber or tube 29 to the tunnel A adjacent the outlet end 39 of the latter, and a return conduit 43 leading from said tunnel adjacent the inlet end 38 thereof to the circulation chamber 24 adjacent the point of communication 32 of the combustion chamber 29 therewith.

The supply conduit 42 includes a short section 44 communicating with the circulation chamber 24 at the top of the latter through the lining 23 thereof, a T-fitting 45 communicating with the section 44, a section 46 connected at one end by a detachable coupling 47 with one branch of the fitting 45 and at its opposite end communicating with the inlet of a blower 48 supported on the top of the oven and driven by a suitable motor 49 and a section 50 leading from the outlet of the blower 48 to two branches 51 which communicate with the interior of the tunnel A adjacent the outlet end of the latter. The other branch of the T-fitting 45 is connected by a detachable coupling 52 with a stack 53 supported independently of the burner unit, as by hangers 54 from the roof 55 of the building within which the furnace is housed. The fitting 45 is provided with dampers 61 and 62 adapted to control communication between said fitting and the conduit section 46 and stack 53 respectively.

The return conduit 43 includes two branches 56 communicating with the interior of the tunnel adjacent the inlet end of the latter and two branches 57 communicating with the circulation chamber 24, said branches 57 being connected by detachable couplings 58 with branches 59 with which communicates a sectional trunk connection 60 leading from the branches 56.

It will be seen that, by disconnecting the detachable couplings 47, 52 and 58, the burner unit B, with the portions 44, 45 and 57 of the conduit connections, may be removed as above described and replaced by a substitute unit having corresponding conduit portions.

It will now be seen that the system described provides for a substantially closed circuit circulation induced by the blower 48, of the air and products of combustion through the heater unit and oven unit, the

hot gases leaving the heater unit adjacent the burner or hottest part of said unit, entering the oven unit adjacent the discharge end of the latter, leaving said oven unit adjacent the inlet end, and returning to the heater at the cooler end of the latter, being thereafter caused to flow about the combustion tube so as to hold down the temperature of the latter and to be reheated thereby. By suitable regulation of the dampers 36, 61 and 62, sufficient, but only sufficient, outside air is admitted to the system to maintain combustion and make up the losses from the oven in charging and discharging, as hereinafter described, thereby fully utilizing all heat units. In starting the furnace, the damper 61 is closed and the damper 62 opened, thereby cutting off the oven and directing all products of combustion to the stack, until the burner unit has then become thoroughly heated. Thereafter, relative adjustment of the dampers 61 and 62 controls the proportion of gases circulated through the oven or discharged from the stack. Such fresh air as is admitted to the system, in addition to that directly supplied to the burner, is admitted through the space 34 of the thimble 25 immediately around the burner end of the combustion tube so as to become immediately heated as well as serving to cool the hottest end of the tube as above explained.

Having thus described our invention, we claim:

1. A heater for drawing furnaces and the like comprising a casing, a circulation chamber extending substantially the length of said casing and enclosed thereby, a long, thin walled combustion tube within said circulation chamber and surrounded thereby and having a length substantially that of said circulation chamber and a diameter relatively small in proportion to its length, said combustion tube having a burner at one end and communicating with said circulation chamber at its other end, and means for admitting air to said circulation chamber surrounding said tube at the end of the latter adjacent said burner.

2. A heater for drawing furnaces and the like, comprising a casing enclosing a circulation chamber and having an opening at one end, a removable thimble in said opening, a burner carried by said thimble, and a combustion tube supported within said circulation chamber in alinement with said burner and removable through said opening when said thimble is removed.

3. A heater for drawing furnaces and the like, comprising a casing enclosing a circulation chamber and having an opening at one end, a removable thimble in said opening, a burner carried by said thimble, and a combustion tube supported within said circulation chamber in alinement with said burner and removable through said opening when

said thimble is removed, said thimble having air inlets opening into said circulation chamber around said combustion tube.

4. A heater for drawing furnaces and the like, comprising a casing enclosing a circulation chamber and having an opening at one end, a removable thimble in said opening, a burner carried by said thimble, supports in said chamber, and a sectional combustion tube alined with said burner and comprising sections carried by said supports and removable through said opening when said thimble is removed. 70

5. A heater for drawing furnaces and the like, comprising a casing enclosing a circulation chamber and having an opening at one end, a removable thimble in said opening, a burner carried by said thimble, supports in said chamber, and a sectional combustion tube alined with said burner and comprising sections carried by said supports and a section carried by said thimble, said sections being removable through said opening when said thimble is removed. 75

6. A heater for drawing furnaces and the like, comprising a casing enclosing a circulation chamber and having an opening at one end, a thimble in said opening comprising spaced coaxial inner and outer members, a combustion tube supported at one end by said inner thimble member and communicating at the other with said chamber, a burner carried by said thimble in alinement with said tube, the space between said thimble members communicating with said chamber around said tube and having air inlets outside said casing, and a damper for controlling said air inlets. 80

7. In a drawing furnace or the like, having an oven, a heater having a circulation chamber for the products of combustion, a combustion chamber communicating therewith, a burner for said combustion chamber, a thimble surrounding said combustion chamber at the end adjacent said burner for admitting air to said circulation chamber and for cooling said combustion chamber at the burner end, and conduits communicating with said circulation chamber adjacent the opposite ends thereof, respectively, whereby heated air may be circulated therethrough to and from the oven of said furnace. 85

8. In a drawing furnace or the like having an oven, a heater having a circulation chamber for the products of combustion, a combustion chamber communicating therewith, a burner for said combustion chamber, a thimble surrounding said combustion chamber at the end adjacent said burner for admitting air to said circulation chamber and for cooling said combustion chamber at the burner end, and conduits communicating with said circulation chamber adjacent the opposite ends thereof, respectively, whereby heat- 90

ed air may be circulated therethrough to and from the oven of said furnace.

9. In a drawing furnace or the like having an oven, a heater having a circulation chamber for the products of combustion, a combustion chamber surrounded by said circulation chamber and communicating therewith at one end, a burner at the opposite end of said combustion chamber, a thimble ⁵surrounding said combustion chamber at the end adjacent said burner for admitting air to said circulation chamber and for cooling said combustion chamber at the burner end, a conduit communicating with said circulation chamber adjacent the burner end of said combustion chamber, and a second conduit ¹⁰communicating with said circulation chamber adjacent the point of communication of said combustion chamber therewith, whereby heated air may be circulated therethrough to and from the oven of said furnace.

10. In a drawing furnace or the like having an oven, a heater having a circulation chamber for the products of combustion, a ¹⁵long, thin-walled combustion tube of relatively small diameter in proportion to its length within said circulation chamber, said tube being surrounded by said circulation chamber and communicating therewith at one end, a burner at the opposite end of said tube, a thimble surrounding said tube at the end adjacent said burner for admitting air to said circulation chamber and for cooling said tube at the burner end, a conduit communicating with said circulation chamber adjacent the burner end of said tube, and a second conduit ²⁰communicating with said circulation chamber adjacent the point of communication of said tube therewith, whereby heated air may be circulated therethrough to and from the oven of said furnace.

11. In a drawing furnace or the like having an oven, a heater having a circulation chamber for the products of combustion, a ²⁵long, thin-walled combustion tube of relatively small diameter in proportion to its length within said circulation chamber, said tube being surrounded by said circulation chamber and communicating therewith at one end, a burner at the opposite end of said tube, a thimble surrounding said tube at the end adjacent said burner for admitting air to said circulation chamber and for cooling said tube at the burner end, a conduit communicating with said circulation chamber adjacent the burner end of said tube, and a second conduit ³⁰communicating with said circulation chamber adjacent the point of communication of said tube therewith, whereby heated air may be circulated therethrough to and from the oven of said furnace.

In testimony whereof we affix our signatures.

RALPH Z. HOPKINS.
